US0D1042883S

(12) **United States Design Patent** (10) Patent No.: **US D1,042,883 S**
(45) Date of Patent: ** Sep. 17, 2024

(54) **BIOREACTOR CABINET**

(71) Applicant: **ADVA BIOTECHNOLOGY LTD.**,
Kiryat Tivon (IL)

(72) Inventors: **Ohad Karnieli**, Kiryat Tivon (IL);
Noam Bercovich, Haifa (IL)

(73) Assignee: **ADVA BIOTECHNOLOGY LTD.**,
Kiryat Tivon (IL)

(**) Term: **15 Years**

(21) Appl. No.: **29/844,251**

(22) Filed: **Jun. 28, 2022**

Related U.S. Application Data

(63) Continuation of application No. 29/721,311, filed on Jan. 20, 2020, now Pat. No. Des. 961,115.

(57) **CLAIM**

The ornamental design for a bioreactor cabinet, as shown and described.

DESCRIPTION

FIG. 1 is a perspective view of a bioreactor cabinet.

FIG. 2 is a front view thereof;

FIG. 3 is a back view thereof;

FIG. 4 is a side view thereof;

FIG. 5 is a side view thereof;

FIG. 6 is a top view thereof;

FIG. 7 is a bottom view thereof; and,

FIG. 8 is a back-perspective view thereof.

The broken lines depict portions of the bioreactor cabinet that form no part of the claimed design.

1 Claim, 8 Drawing Sheets
